[57] **CLAIM**

The ornamental design for a leg elevating support for a sunbather, as shown.

DESCRIPTION

FIG. 1 is a side elevational view of a leg elevating support stand for a sunbather showing my design;

FIG. 2 is an edge view taken from the right in FIG. 1; FIG. 3 is an elevational view showing the side opposite that shown in FIG. 1;

FIG. 4 is an edge view taken from the left in FIG. 1;

FIG. 5 is a bottom plan view; and

FIG. 6 is a top plan view thereof.
